UNITED STATES PATENT OFFICE

101,205

DESIGN FOR A SHOE

Albert F. Bancroft, Newton, Mass., assignor to
Bancroft-Walker Company, Waltham, Mass., a
corporation of Massachusetts

Application July 16, 1936, Serial No. 63,879

Term of patent 3½ years

To all whom it may concern:

Be it known that I, Albert F. Bancroft, a citizen of the United States, residing at Newton, in the county of Middlesex and Commonwealth of Massachusetts, have invented a new, original, and ornamental Design for a Shoe, of which the following is a specification, reference being had to the accompanying drawing, forming a part hereof, in which

Fig. 1 is a plan view of a shoe showing my new design,

Fig. 2 is a view of the shoe in side elevation. In both figures the rear portion and the toe portion of the shoe are shown conventionally in dotted lines, the dominant feature of the design residing in the portion shown in full lines.

I claim:

The ornamental design for a shoe substantially as shown and described.

In witness whereof, I have affixed my signature hereto.

A. F. BANCROFT.
